WICK TYPE DEVICE FOR EXPOSING
LIQUIDS TO THE ATMOSPHERE

Ralph W. Walsh, Westminster, Calif.

Application August 25, 1950, Serial No. 181,376

3 Claims. (Cl. 299—20)

1

This invention relates to improved devices for exposing liquids to the atmosphere, as for instance for the purpose of dispelling a volatile insecticide, deodorizing fluid, or the like into the air, or for exposing a non-volatile insecticide for direct contact by insects.

The invention is particularly concerned with devices of a known general type comprising a bottle or other container for holding a body of liquid, and a liquid-carrying wick receivable entirely within the container when the device is not in use but adapted when in use for partial withdrawal through the neck of the container to a condition of direct exposure to the atmosphere. The general object of the invention is to provide improvements for facilitating the handling of such devices, and especially for simplifying their conversion between open and closed conditions. Particularly contemplated is an improved wick type device of the above character in which movement of the wick between its retracted and outwardly projecting positions is facilitated by interconnecting the usual container cap and wick for movement together, so that removal or replacement of the cap serves to itself automatically withdraw or retract the wick. Thus, the entire conversion process between open and closed conditions consists merely in opening and closing the cap of the bottle. Preferably, the connection between the cap and wick is formed in a manner permanently retaining the cap to the wick, to thus attain the added advantage of preventing loss or misplacement of the cap by reason of its removal from the bottle.

Since the cap in a device of this character should be of the screw type adapted for removal from the bottle only by rotation relative to the container, a further object of the invention is to so form the connection between the wick and cap as to avoid any interference with such rotation of the cap. For this purpose, I preferably interconnect the cap and wick by a swivel connection permitting rotation of the cap without corresponding rotation of the wick. To assure most effective control of the wick movements, the wick and cap may be interconnected in a manner permitting this rotation while maintaining the wick and cap in substantially fixed relation axially of the bottle neck, so that the wick follows substantially exactly the removal and replacing movements of the cap.

Structurally, I prefer to connect the wick to the cap by means of a connecting element extending from a central portion of the cap through an opening in a transverse outer or upper portion of

the wick and having a head at the underside of that upper portion of the wick preventing withdrawal of the element. The head of this connecting element may bear against a backing member at the underside of the wick to positively retain the head against upward movement through the opening in the wick. Similarly, the head may be engageable at its underside with the upper end of a wick reinforcing member to limit downward movement of the connecting element and cap. The upper end of the connecting element may be fastened to the cap by reception within a recess in a boss or lug projecting downwardly from the center of the cap.

15 The above and other features and objects of the present invention will be better understood from the following detailed description of the typical embodiment illustrated in the accompanying drawing in which:

20 Fig. 1 is a perspective view of a preferred embodiment of the invention showing the wick and wick cap in position for use;

25 Fig. 2 is an enlarged fragmentary vertical section through the upper portion of the device and taken on line 2—2 of Fig. 1; and

30 Fig. 3 is a further enlarged perspective view of the backing member for engaging the head of the connecting element at the underside of the upper transverse portion of the wick.

35 Referring first to Fig. 1, the illustrated device comprises essentially a bottle 10 for containing a body of the liquid to be exposed to the atmosphere, a wick assembly 11 by which the liquid is carried from its initial position at the inside of the bottle to a location of direct contact with the atmosphere at the outside of the bottle, a bottle cap 12 and a connecting element 13 by which the cap is rotatably connected to the wick. The bottle 10 is of conventional formation having an upper neck or mouth portion 14 through which liquid is filled into and removed from the bottle and externally threaded for connection to the internally threaded cap 12.

40 The wick assembly includes a flat vertically elongated reinforcing member 15, formed of wood or any other suitable relatively stiff material and of a width slightly less than the diameter of the opening within the neck of the bottle. The wick element itself, designated 16, is in the form of an elongated strip of fibrous and porous material of approximately the same width as the reinforcing member 15. This elongated wick element extends upwardly at one side of reinforcing member 15 and is then doubled back at the upper end of the reinforcing member and extends downwardly at

its opposite side. The upper end of the wick thus forms a short portion 17 extending generally horizontally or transversely of the bottle neck. The wick may be fastened to the reinforcing element 15 in any suitable manner, as by a pair of wire-like staples 18 extending entirely through both thicknesses of the wick and through the intermediate reinforcing member. The lower free ends 19 of the wick element are of sufficient length to assure proper contact between the wick and the liquid in the upwardly projecting Fig. 1 position of the wick.

The cap and wick are rotatably interconnected by an elongated screw-like connecting element 13 extending downwardly from the center of the cap through a vertical opening 20 in the center of the upper transverse portion 17 of the wick element. At the underside of this transverse portion of the wick, I provide an elongated plate-like backing member 21 containing a central opening 22 through which connecting element 13 passes. At its lower end, connecting element 13 has an enlarged head portion 23 engageable with the underside of backing member 21 about opening 22 to limit the upward movement of the cap relative to the wick assembly. It is noted also that the underside of head 23 is positioned directly above and is engageable with the upper end of the reinforcing member 15 to limit downward movement of the cap relative to the wick assembly. As a result of this connection, the cap is free for rotation relative to the wick to permit attachment of the cap to and its removal from the bottle neck, while the wick and cap are maintained against substantial relative axial or vertical movement so that the wick follows substantially exactly all vertical movements of the cap.

Cap 12 has at its center a downwardly projecting boss or socket formed integrally with the main portion of the cap and containing a central vertical bore 26 into which the upper end of connecting element 13 is threadedly connected. The lower end of boss 25 contains an enlarged counterbore 27 within which is received a body of cement 28 for supplementing the effect of the threaded joint and positively locating the connecting element relative to the cap.

When the device is not in use, the wick assembly 11 is retracted downwardly to a position entirely within the bottle, and cap 12 is threadedly connected in the usual manner to neck 14 of the bottle. In order to prepare the device for use, it is then necessary merely to unscrew cap 12 and raise it relative to the bottle to the condition of Fig. 1. As the cap is unscrewed, it is permitted to rotate relative to the wick assembly by virtue of the swivel connection through element 13. When the cap is elevated to its Fig. 1 position, engagement of head 23 of the connecting element with backing member 21 at the underside of the upper portion of the wick effects corresponding upward movement of the wick to its Fig. 1 position. If the liquid within the bottle is of a volatile nature, it then passes upwardly through the wick by capillary action and evaporates into the air. If of a non-volatile nature, the liquid is exposed to the atmosphere at the surface of the wick to produce whatever effect may be intended. It is contemplated that for some types of liquid which may be incapable of feeding to the upper portion of the wick by capillary action, it may be desirable to manually lower the wick at given intervals into the bottle for engagement with the

body of liquid. When it is desired to lower the wick for this purpose, or to close the bottle, it is necessary merely to move the cap downwardly to its initial position of engagement with the neck. The cap may then be screwed onto the neck by virtue of its freedom for rotation relative to the wick.

I claim:

1. A device for exposing a liquid to the atmosphere comprising a container having an upwardly projecting neck portion containing an opening, a cap for closing said neck portion of the container and threadedly connectible thereto, a wick assembly receivable within said container and adapted to be partially withdrawn through said neck to an upwardly projecting position of direct exposure to the atmosphere, said wick assembly including a vertically extending flat relatively stiff reinforcing member and a wick element extending upwardly at one side of said member and then doubled back to extend downwardly at the opposite side of the member, said wick element forming a short generally horizontally extending portion at its upper end directly above the reinforcing member, a connecting element carried by the cap and extending downwardly from a central portion thereof through an opening in said upper horizontal portion of the wick element, a backing element extending horizontally at the underside of said upper horizontal portion of the wick element and containing an opening registering with said opening in the wick element and through which the connecting element extends, said connecting element having an enlarged head portion engageable against the underside of said backing element and the upper end of said reinforcing member to limit the movement of the connecting element axially of the neck relative to the wick assembly, said connecting element being rotatable relative to the wick assembly about the axis of the neck, whereby the cap is rotatable relative to the wick for attachment to and removal from the neck, and axial movement of the cap in opposite directions serves to withdraw the wick assembly to said outwardly projecting position and retract it from that position into the container.

2. A device for exposing a liquid to the atmosphere comprising a container for holding a body of the liquid and having a neck portion containing an opening, a cap adapted to close said neck of the container and threadedly connectible thereto, a wick receivable within said container in contact with the liquid therein and having a portion adapted to be withdrawn through said neck of the container to an outwardly projecting position of exposure to the atmosphere, said cap having a lug formed integrally therewith and projecting inwardly from the center thereof, a connecting element having an outer end received within a bore formed in said lug and threadedly connected thereto, and a swivel connection between the inner end of said connecting element and the outer end of said wick interconnecting them for movement together axially of the neck while permitting their relative rotation, whereby the cap is rotatable relative to the wick for attachment to and removal from the neck, and axial movement of the cap serves to withdraw the wick from said outwardly projecting position and retract it from that position into the container.

3. A device for exposing a liquid to the atmosphere comprising a container having an upward

ly projecting neck portion containing an opening, a cap for closing said neck portion of the container and threadedly connectible thereto, a wick assembly receivable within said container and adapted to be partially withdrawn through said neck to an upwardly projecting position of direct exposure to the atmosphere, said wick assembly including a vertically extending flat relatively stiff reinforcing member and a wick element extending upwardly at one side of said member and then doubled back to extend downwardly at the opposite side of the member, said wick element forming a short generally horizontally extending portion at its upper end directly above the reinforcing member, said cap having a lug formed integrally therewith and projecting downwardly from the center thereof, an elongated wire-like connecting element having an upper end threadedly connected into the underside of said lug, cement at the lower end of said threaded connection fastening said element to the lug of the cap, said connecting element extending downwardly from its point of connection to the cap through an opening in said upper horizontal portion of the wick element, a backing element extending horizontally at the underside of said upper horizontal portion of the wick element and containing an opening registering with said opening in the wick element and

through which the connecting element extends, said connecting element having an enlarged head portion engageable against the underside of said backing element and the upper end of said reinforcing member to limit the movement of the connecting element axially of the neck relative to the wick assembly, said connecting element being rotatable relative to the wick assembly about the axis of the neck, whereby the cap is rotatable relative to the wick for attachment to and removal from the neck, and axial movement of the cap in opposite directions serves to withdraw the wick assembly to said outwardly projecting position and retract it from that position into the container.
